UNITED STATES PATENT OFFICE.

GEORGE W. SCHNEIDER, OF ARGENTA, ARKANSAS, ASSIGNOR OF ONE-THIRD TO
MONBOE MERRETT, OF ARGENTA, ARKANSAS.

DRAFT-GEAR.

1,168,569.

Specification of Letters Patent. Patented Jan. 18, 1916.
Application filed July 17, 1915. Serial No. 40,450.

To all whom it may concern:

Be it known that I, GEORGE W. SCHNEIDER, a citizen of the United States, residing at Argenta, in the county of Pulaski and State of Arkansas, have invented a new and useful Draft-Gear, of which the following is a specification.

The device forming the subject matter of this application is adapted to be assembled 10 with a draft rigging of known form, to constitute a support therefor, the structure being of peculiar utility upon railway vehicles.

The invention aims to provide novel 15 means for supporting the draft beam and the coupler, so that these parts will be permitted to have the necessary movements, accidental misplacements thereof being prevented.

It is within the province of the disclosure 20 to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed can be made within the scope of what is claimed without departing from the spirit of the invention.

In the accompanying drawings:—Figure 1 35 shows in longitudinal section, one form of draft rigging wherewith the device forming the subject matter of this application has been assembled, parts being broken away; Fig. 2 is a side elevation showing a 40 portion of the structure delineated in Fig. 1, parts being in section; Fig. 3 is a vertical transverse section wherein sundry parts of the draft rigging appear in elevation; Fig. 4 is a cross section taken approximately on 45 the line 4—4 of Fig. 1; Fig. 5 is a top plan of the supporting arm; Fig. 6 is a side elevation of the supporting arm; Fig. 7 is a fragmental cross section showing a slight modification in the invention.

The device forming the subject matter of 50 this application is adapted to be employed in connection with a known form of draft rigging, and this rigging will first be described, proper indication being made at the

point where the description of parts considered to be new begins.

The numeral 1 designates the floor of a railway vehicle, the numeral 2 designating longitudinal sills.

The numeral 3 indicates an end sill, the 60 numeral 4 designates a transverse buffer beam, and the numeral 5 denotes a buffer block on the buffer beam.

A draft beam 6 is shown, the same having a vertical opening 7. 65

Secured in a manner to be described hereinafter to the forward end of the draft beam 6 is a coupler 8.

For the parts above described and enumerated no novelty is claimed, saving in so 70 far as they may coöperate with elements to be described hereinafter.

In carrying out the present invention there is provided an arm 9 located beneath the draft beam 6 and the coupler 8. Bolts 75 10 or other securing elements are employed for uniting the coupler 8 with the draft beam 6, and in the present embodiment of the invention, the bolts 10 are elongated sufficiently so as to pass through openings 80 11 in the arm 9, thereby to hold the arm in place, as shown best in Fig. 1. At its forward end, the arm 9 is provided with a table 12 which bears against the under face of the coupler 8, intermediate the ends of 85 the coupler, the table 12 having at its sides, upright flanges 14 which lie upon opposite sides of the coupler, as shown in Fig. 3. The arm 9 embodies longitudinal side flanges 15 which, at their rear ends, may 90 coact with the side faces of the draft beam 6, one of the flanges 15 preferably being cut away at its rear end, as indicated at 16 in Fig. 5, in order to accommodate certain enlargements sometimes found upon the 95 draft beam 6. Intermediate its ends, the arm 9 is supplied with a transverse rib 17, which, as shown in Fig. 1, engages the forward end of the draft beam 6 and aids in holding the arm 9 in place. Adjacent its 10 rear end, the arm 9 is provided with spaced projections 18 which bear against the draft beam 6 at opposite sides of the opening 7 therein. In the arm 9 between the projections 18, there is formed an elongated opening 19 lying below the opening 7 in the draft beam 6. About the opening 19 in the arm 9, and upon the under surface of the

arm, a concaved seat 20 may be formed. The flanges 14 of the arm are provided with eyes 21, receiving the lower ends of upwardly extended chains 22, assembled with 5 eye bolts 23 mounted in the buffer beam 4.

The invention comprises an upright support in the form of a rod 24, extended through the opening 7 in the draft beam 6, and through the opening 19 in the arm 9. 10 The support 24 is provided adjacent its lower end with an opening 25 through which may be straddled a key 26 upholding an abutment 27, engaging the lower end of a helical compression spring 28, the upper end 15 of which is engaged by an abutment 29 having a rounded end 30 received in the concaved seat 20 of the arm. Pivotally mounted in an eye 42 formed at the upper end of the rod or support 24 is a link 31, concatenated with a rectangularly disposed link 32, the upper end of which is enlarged to receive a transverse pin 33, concaved downwardly intermediate its ends as shown at 34 in Fig. 4. Upon the longitudinal sills 2, 20 U-shaped brackets 35 are placed, the same being secured by means of attaching elements 36. The brackets 35 are provided, as shown in Figs. 2 and 1 with downwardly concaved seats 37 in which the ends of the 25 pin 33 are received. When the car is of steel construction, the sills 2 may be replaced by channels 38 as shown in Fig. 7, and under such circumstances, the brackets may be of hook-shape, the upper arms thereof being 30 united by means of attaching elements 40 with the upper flange of the channel 38. The seat 41 is of the sort hereinbefore described and indicated at 37.

The arm 9, being attached to the draft beam 40 6 by means of the bolts 10, serves to uphold the beam and maintain it in line with the coupler 8 as Figs. 1 and 3 will clearly show. The spring 28 absorbs the shock produced by a downward movement of the beam 6 and 45 the coupler 8 during the coupling operation, and serves to raise these parts to their normal positions. The spring 28, further, permits the beam 6 and coupler 8 to have the necessary vertical movement while the vehicle of which the draft rigging constitutes 50 a part is running on the road. If it is desired to vary the compressive effort of the spring 28, washers (not shown) may be inserted between the abutment 27 and the key 55 26, as a person skilled in the art will understand readily. Owing to the presence of the links 31 and 32, the draft rigging may be permitted to have the necessary reciprocating movement in a longitudinal direction. 60 When the draft rigging moves longitudinally as above described, the ends of the pin 33 are adapted to ride back and forth in the seats 37, and because these seats are downwardly concaved, the pin 33 will be returned 65 to a centralized position. Further, the link

42 will be centralized on the pin 33, because the pin is downwardly concaved as shown at 34 in Fig. 4. The chains 22 act as safety devices supporting the draft mechanism should the rod 24 or any parts assembled therewith give way. The rib 17 and the projections 18 on the arm 9 coat with the draft beam 6 to sustain the arms against longitudinal strains as hereinbefore pointed out, and as evident from Fig. 1.

Having thus described the invention, what is claimed is:

1. In a device of the class described, a car; opposed brackets mounted on the car and provided with downwardly concaved seats extended longitudinally of the car; a cross member having its ends slidably mounted in the seats; a draft rigging; and means for connecting the draft rigging with the cross member.

2. In a device of the class described, a car; a cross member carried thereby and having a downwardly concaved upper edge; a draft rigging; and means for supporting the draft rigging, said means engaging the concaved upper edge of the cross member.

3. In a device of the class described, a car; opposed brackets mounted on the car and provided with downwardly concaved seats extended longitudinally of the car; a cross member having its ends slidably lodged in the seats, the upper edge of the cross member being downwardly concaved; a draft rigging; and supporting means for the draft rigging, the supporting means being slidably engaged with the concaved upper edge of the cross member.

4. In a device of the class described, a car; a draft rigging embodying a draft beam and a coupler assembled therewith; an arm secured intermediate its ends to the draft beam and bearing at its forward end against the coupler; a support extended through the arm and the beam; means for assembling the upper end of the support with the car; an abutment on the lower end of the support; and a spring interposed between the abutment and the arm.

5. In a device of the class described, a car; a draft rigging carried by the car and comprising a draft beam and a coupler assembled with the draft beam, the draft beam being provided with an opening; an arm bearing at its forward end against the lower face of the coupler; a securing element uniting the coupler, the draft beam and the arm; and the arm being provided with projections, one of which engages the forward end of the beam, the other of which engages the beam within the contour of the opening.

6. In a device of the class described, a car; a draft rigging carried by the car and comprising a draft beam and a coupler assembled with a draft beam, the draft beam

being provided with an opening; an arm bearing at its forward end against the lower face of the coupler; a securing element uniting the coupler, the draft beam and the arm; and the arm being provided with projections, one of which engages the forward end of the beam, the other of which engages the beam within the contour of the opening; a support extended through the opening; means for assembling the upper end of the support with the car; an abutment on the lower end of the support; and a spring interposed between the abutment and the arm.

Copies of this patent may be obtained for five cents each, by addressing the "Commissioner of Patents, Washington, D. C."

7. In a device of the class described, a 15 car; a draft rigging embodying a draft beam and a coupler assembled therewith; an arm secured to the draft beam and bearing upon the coupler in advance of the draft beam; and flexible beams for connecting 20 the arm with the car in advance of the beam.

In testimony that I claim the foregoing as my own, I have hereto affixed my signature in the presence of two witnesses.

GEORGE W. SCHNEIDER.
